UNITED STATES PATENT OFFICE.

WILLIAM S. WELLS, OF BETHLEHEM, PENNSYLVANIA, ASSIGNOR TO BENJAMIN EASTWOOD COMPANY, OF PATERSON, NEW JERSEY, A CORPORATION OF NEW JERSEY.

LOOM.

Application filed March 15, 1924. Serial No. 699,391.

This invention relates to looms for weaving in which the reed is arranged to yield rearwardly.

One object of the invention is to provide for the yielding of the reed should a shuttle or other obstruction intervene between it and the fell of the fabric during the forward stroke of the batten and yet to provide for establishing resistance to yielding of the reed after the batten during said stroke has passed a given position, to the end that when the obstruction intervenes in the event that only a comparatively few of the warp threads are up or down and for this or any other reason the warp is frail there may occur a yielding of the reed and yet under normal conditions the reed will meet the fell of the fabric with the proper degree of impact.

Another object is to provide novel and efficient means for controlling the yielding of the reed, one of such means being in the example hereinafter set forth afforded by that part of the mechanism which controls the reed at the moment of the beating up and the other being afforded by that part of said mechanism which controls the reed when a shuttle or other obstruction intervenes between it and the fell of the fabric.

In the drawings,

Fig. 1 is a front elevation of a batten, a rearwardly yielding reed thereon, and the mechanism of this invention which controls the reed, certain parts appearing in section and others broken away;

Figs. 2 and 3 are vertical front-to-rear sections on a larger scale, taken on the line 2—2, Fig. 1, the batten being respectively in the one case fully forward and in the other back;

Fig. 4 is a similar section in the same plane, and showing the reed to have yielded rearwardly due to pressure of an obstruction between it and the fell of the fabric;

Fig. 5 is a plan, partly in section, of substantially what is shown in Fig. 1;

Fig. 6 is a plan of certain parts with the batten removed, being on a larger scale than Fig. 5; and

Figs. 7 and 8 show certain details.

The frame is indicated at *a*. *b* designates the usual lay swords, which in this case are bent backward, as at *b'*, near their upper ends, and *c* is the batten, *d* being the shut-

tle thereon. *e* is the breast beam and *f* the knock-off shaft having a handle *f'* and forming the controlling member of a well-known means for stopping the loom and consequently the batten-including structure, the normal position of the knock-off shaft when the loom is running being that shown in Figure 2; and *g* is an arm affixed to and depending from and hence forming a part of the rocking structure constituted by the knock-off shaft.

The reed is here taken as including the reed proper *i* and a frame in which it is mounted, constructed thus: with upper and lower rails *j* and *k* grooved to receive the reed proper and with two uprights *l* (each bent backward at *l'* as shown) which connect the ends of the rails and have forward ears *l''* (Fig. 5) receiving pivots or studs *m'* on angle brackets *m* secured to the lay swords. As in my application No. 660,293, Patent No. 1,530,530, the reed is provided with counterweights *n* upstanding therefrom, their depending extensions *n'* being set in recesses *m''* in the ends of the upper rail *j* and clamped between the latter and the uprights *l*.

One upright *l* has a depending lug *l''* whose nose is normally rearwardly abutted by a cam-rise *o'* formed on the upstanding arm of a lever *o* which may be fulcrumed on a stud *o''* on the adjoining lay-sword, the other and forward arm of the lever being pulled downwardly by a spring *p* attached to the lay-sword. The spring *p* exerts comparatively little force on the lever so that while the friction that exists between *l''* and *o'* is perfectly adequate to prevent backward swinging of the reed as the result of inertia when the batten goes forward, if an obstacle, as the shuttle *d*, intervenes between the reed and the fell of the cloth during the forward stroke, the reed will cam back the lever *o*, yielding rearwardly from the position in Figures 2 or 3 to the position in Figure 4. When the reed is in the first-named of these positions it abuts forwardly against a stop afforded by the back face of the batten, against which a pair of catch-plates *q* depending from the back of the reed may abut.

After the batten-including structure during each stroke has passed a given position, to wit, when it has approached sufficiently

near to the fell of the cloth so that the shuttle or any other obstacle is not likely to intervene, means now to be described establishes resistance to backward yielding of the reed and maintains the same until such stroke is completed. In the present adaptation said means takes the form of a coupling mechanism which couples the reed structure to the batten-including structure, but with a certain amount of yield. Thus:

Bolted to the under side of the batten and therefore forming a part of the structure including the same and the lay swords is a pair of brackets *r* which have forward seats *r'* and from which upstand the bolts *s*. On two horizontally alined studs *t* in these brackets are fulcrumed a pair of bell-crank levers *u* which have their forwardly projecting arms formed as pads *u'* to rest on the seats *r'* under the pressure of strong spiral springs *v* coiled about the bolts *s* and interposed between said pads and adjustable nuts *s'* on the bolts; the upwardly projecting arms *u*² of the levers have arranged to rock therein a shaft *w* which has clamped thereto, by screws *x*, the pair of hooks or latches *y* adapted to be raised and catch the catch-plates *g*, thus to couple the reed and batten-including structures together. The coupler proper formed by shaft *w* and the latches is normally held depressed by a spiral spring *w'* (Fig. 1) secured at one end to a collar on the shaft and having a roller *w*² at the other end to bear against the bottom face of the batten. The coupling is effected during the forward stroke of the batten, as stated, from an actuator in the form of an abutment, here a roller, *z* secured to one side of the loom frame, through means which has provision for yielding elastically should the latches perchance be raised without the reed structure being fully forward where the hooks of the latches properly clear or take behind the catch-plates. Thus another rock-shaft *2* is journaled in the right-hand bracket *r* and in a suitable bearing on the adjoining lay-sword and has at its right end an arm *3* (Fig. 1) fixed thereon in the path of and adapted to engage the abutment *z* and at its left-hand end the following parts, to wit: a fixed head *4* (Fig. 8) having a lateral hook-extension *4*^a, a lever *5* fulcrumed on the shaft next to the head and equipped with a roller *5*^a to bear against the under side of the right-hand latch *y* of the coupler proper, and a spring *6* coiled about the shaft and having one end hooked over the hook-extension and its other end hooked under the lever *5* and thereby normally holding the latter pressing against the hook-extension. When the batten moves forward contact of arm *3* of rock-shaft *2* with the abutment *z* rocks the latter clockwise (Fig. 2), thus elevating the lever *5* which in turn elevates the coupler

proper, the necessary yield of the lever *5* at this time being permitted by spring *6*; when the batten moves back the rocking structure including shaft *2* and its adjuncts turns anti-clockwise to a limit afforded by contact of an arm *2*^a thereon with the lay-sword (Figs. 1 and 6), the coupler proper falling clear of the reed.

Under normal conditions the coupling of the reed to the batten-including structure through the coupling means described occurs on every forward stroke of said structure, the necessary yield of the reed on impact with the fell of the fabric being afforded by the springs *v*. But if an obstruction intervenes between the reed and the fell the reed will yield rearwardly, as already described, overcoming the resistance offered by the lever *o*.

As in my said application, I may provide a dagger *7* which is pivoted beneath the batten in a bracket depending therefrom and shown dotted at *8* in Fig. 2 and which, when it is cleared by a set-screw *9* depending from the reed and normally overlying the rear end of the dagger, falls so as to engage the arm *g* and thus cause stopping of the loom by rocking the knock-off shaft, this occurring when, in a forward movement of the batten, the presence of an obstacle in the shed results in rearward yielding of the reed.

Having thus fully described my invention, what I claim as new and desire to secure by Letters Patent is:

1. In combination, a batten-including structure movable back and forth, a reed rearwardly movable therein, and means to establish yielding resistance to the backward movement of the reed after said structure during each forward stroke thereof has passed a given position and thereupon maintain said resistance until such stroke is completed.

2. In combination, a batten-including structure movable back and forth, a reed rearwardly movable therein, and means to establish spring resistance to the backward movement of the reed after said structure during each forward stroke thereof has passed a given position and thereupon maintain said resistance until such stroke is completed.

3. In combination, a batten-including structure movable back and forth, a reed structure rearwardly movable therein, and means to yieldingly couple the two structures together and thereby oppose backward movement of the reed structure after the first structure during each forward stroke thereof has passed a given position.

4. In combination, with a support, a batten-including structure movable back and forth therein, a reed structure rearwardly movable in the first structure, and movable

- means arranged on one of the structures and including a yielding coupling adapted on movement of said means to couple the two structures together and thereby oppose backward movement of the reed structure, the support having a part thereof adapted to be wiped by said means during a forward stroke of the first structure and thereby cause such movement of said means.
5. In combination, with a support, a batten-including structure movable back and forth therein, a reed structure rearwardly yieldable in the first structure, and yielding mechanism, movable back and forth with said structures, for coupling them together and thereby opposing said yielding of the reed structure after the first structure during each forward stroke thereof has passed a given position including a coupling member movable into and out of the coupling position and also including a device movable to move the coupling, the support having a part thereof adapted to be wiped by said device during such stroke.
6. In combination, a batten-including structure, a reed rearwardly yieldable therein, a lever fulcrumed in said structure, a coupler to connect the lever with said reed and movable into and out of coupling engagement with one of them, a spring opposing movement of the lever on its fulcrum transmitted thereto through the coupler from the reed on pressure being exerted rearwardly on the reed, and means to control the movement of the coupler. 25 30 35
7. In combination, a batten-including structure, a reed yieldable rearwardly therein, and a lever having a cam-rise engaged by, and frictionally opposing the yielding of, the reed and past the summit of which the reed moves in yielding, said lever being spring-held to oppose yielding of said reed. 40

In testimony whereof I affix my signature.

WILLIAM S. WELLS.
